UNITED STATES PATENT OFFICE.

JOZEFKA KECZUR, OF WEST SELKIRK, MANITOBA, CANADA.

DESIGN FOR A COMBINATION COLORED CHIPPED-GLASS FRAME AND MIRROR.

Application filed December 12, 1922. Serial No. 4,584. Term of patent 7 years.

To all whom it may concern:

Be it known that I, JOZEFKA KECZUR, a citizen of Ukraine, residing at West Selkirk, in the Province of Manitoba and Dominion of Canada, have invented a new, original, and ornamental Design for Combination Colored Chipped-Glass Frame and Mirror, of which the following is a specification, reference being had to the accompanying drawing, forming part thereof.

The figure is a front elevational view of a combination colored chipped glass frame and mirror, showing my new design.

I claim:

The ornamental design for a combination colored chipped glass frame and mirror, as shown.

JOZEFKA KECZUR.
